UNITED STATES PATENT OFFICE.

SETH T. HARSHAW, OF COHOES, NEW YORK.

LOOPING-MACHINE.

No. 818,874.

Specification of Letters Patent.

Patented April 17, 1906.

Application filed February 18, 1904. Serial No. 193,462.

To all whom it may concern:

Be it known that I, SETH T. HARSHAW, a citizen of the United States, residing at Cohoes, in the county of Albany and State of New York, have invented new and useful Improvements in Looping-Machines, of which the following is a specification.

This invention relates to looping-machines for uniting two pieces of knit fabric by their loops by a stitching mechanism adapted to operate with a thread or yarn to produce an elastic chain of stitches for holding said two pieces of knit fabric elastically united. This machine for uniting the two pieces of knit fabric by the stitches is adapted to render the joined fabric capable of being stretched to the tearing-point of either of the two knit fabrics without breaking the thread or yarn uniting said fabrics, and the chain stitches produced consist each of a loop-form stitch for uniting each pair of contiguous loops of the two pieces of knit fabric and for alternating a second loop between the latter and the pair of the next succeeding loops of the fabrics to be joined.

The invention further consists in the novel devices, elements, and parts hereinafter particularly described, and set forth in the claims.

The purposes and advantages of this invention may be fully understood from the following description when taken in connection with the accompanying drawings, (in five sheets,) forming a part of this specification, in which—

Figure 1 is a plan view of a machine embodying this invention. Fig. 2 is a side elevation of the same. Fig. 3 is an elevation of the same viewed from the opposite side. Fig. 4 is a side view, on an enlarged scale, of the mechanism for operating the needle and the looper, a portion of the oscillating plate and its adjuncts being shown in action. Fig. 5 is a plan view of the same. Fig. 6 is a front view of the same. Figs. 7, 8, and 9, respectively, illustrate the successive movements and operations of the needle and looper in connection with two pieces of knit fabric to produce the elastic chain-stitch uniting said fabrics. Fig. 10 illustrates the movement of the looper in relation to the needle, and Fig. 11 is a diagram illustrating the elastic loop-form stitching produced and joining intermediate loops of the knit fabrics.

Similar characters of reference refer to similar parts throughout the several views.

In the drawings, A, Figs. 1, 2, 3, 4, and 6, is a stationary bed-plate adapted to be supported by the usual work-table, Fig. 3. This bed-plate supports the parts of the machine which operate with the knit fabrics to be joined and also the mechanism for actuating the same. Projected from said bed-plate A is the vertical bracket A', Figs. 2, 3, 4, and 5, which bracket has attached to it and rigidly supports the horizontal arm A², which terminates in the transverse horizontal sleeve A³. This arm A², with its horizontal sleeve A³, supports the vertical oscillating circulating plate E, which carries the two pieces of knit fabric to be stitched together by means of the oscillating device B, consisting of the horizontal shaft B' and vertical shaft B² at right angles to one another and suitably joined by means of piece E⁴.

The vertical shaft B², projecting from piece E⁴, is inserted in hub E', projecting upward from the center of oscillating plate E, as shown in dotted lines in Figs. 2 and 3, and secured by means of set-screw E⁵. The horizontal shaft B', projecting from shoulder b of piece E⁴, Figs. 2 and 3, passes freely through sleeve A³ and receives on its outer end the split sleeve C' of lever C and is secured by clamping-screw C². This split sleeve and clamping-screw are for adjusting the oscillating plate E to any desired angle.

The circular oscillating plate E is shown in Figs. 1, 2, and 3. It carries on its circumferential portion the revoluble ring F, which ring is provided with points f. The plate E is provided with an annular shoulder e for receiving the ring F, which ring is secured in place by keeper F', held by screws e'. (Shown in 2.) The points f f (shown in the several figures) are, in form of construction and manner of being secured in place, the same as are commonly used in this class of machines by the trade, and therefore need no particular description.

Suitable mechanism is provided for revolving the ring F and its points ff with an intermittent movement. This mechanism which I at present preferably employ consists of the horizontal shaft G', Figs. 2 and 3, carrying on one end the pinion G², which engages with teeth G³ on the under side of the revoluble ring F. The opposite end of shaft G' carries ratchet-wheel H. This shaft and its adjuncts are supported in suitable bearings G, projecting from the under side of the os-

100

105

110

2
cillating circular plate E, as shown in Figs. 2 and 3, and when the ratchet-wheel actuates shaft G' the points f on the periphery of ring F are advanced by means of pinion G², acting 5 with teeth G³ on said ring. The toothed portion of the ratchet-wheel H projects through opening e², provided in plate E and inside and free of the line of travel of ring F, and the relative proportion of the toothed surface G³ 10 to that of pinion G² is in this present machine as twenty to one, though these proportions may be changed as necessity may require.

The ratchet-wheel H has teeth h', substantially as shown in Fig. 2 and 3, the bearing- 15 surface of the teeth being on a line radial with its center of rotation, while the rear side is relatively to the same at an angle of forty-five degrees. The dog H' is at the outer end of reciprocating arm H², and the 20 opposite end of said arm is connected with eccentric H⁴ by eccentric-ring H³, Figs. 1 and 2, in the manner generally practiced. This eccentric imparts a reciprocating movement 25 to the arm H² and is revolved at a speed twice that of the eccentric D, which, through lever C, oscillates vertically the plate E and its ring F. This is accomplished by pinion D⁴ on 30 drive-shaft I and gear-wheel D³ on shaft D', as shown in Figs. 1, 2, and 3, so that a point f and a space are each presented to needle K at each oscillation of plate E.

Suitable mechanism is provided with the ratchet-wheel H for so controlling the intermittent rotation of the same that each forward movement of the teeth may be completed simultaneously with the completion of the upward movement of the edge of ring F, adjacent the stitching mechanism. My preferred mechanism is shown in Figs. 1, 2, and 35 to consist of detent j, carried by lever J, provided with sleeve j' and working on stud j², projected from a side of standard J', projected from the upper side of plate E. This 40 detent j operates with the front edge of each tooth when at its zenith and checks the former movement of the same at the proper time. Mechanism is also provided by which the dog H' is quickly lifted out from engagement 45 with the ratchet-teeth h'. My preferred mechanism at the present time consists of fulcrum J², provided between upwardly-projected guides j⁴ j⁴ on standard J', as shown in Figs. 1, 2, and 3. This fulcrum J² serves, with the motion of eccentric H⁴, operating said arm H², to cause said arm to act 50 as a lever to lift dog H' quickly out of engagement with the ratchet-teeth when each forward movement of the ring F of points f' is completed. The detent j in Fig. 2 is shown 55 to have its working side and bottom lines correspond with the angles of the ratchet-wheel h', so as to prevent any rotary motion of ring F while the dog H' is reaching forward to gather another tooth.

60 It will be seen by referring to Fig. 2 that the

circular plate E and its adjuncts are adapted to be oscillated so that a movement of the points f may be had toward and away from the needle K, as shown by dotted line x in Fig. 2, the center of oscillation being the center of the sleeve A³. By this means the points f, carrying the loops of the knit fabrics z and z', to be joined, will be presented in proper position for the passage of the thread from the needle K, and when this operation 70 has been completed to allow the points f to drop by the downward tip of plate E, (indicated by broken and dotted lines x in Fig. 2,) so that the needle may advance again toward the looper provided and over the loops z z' to 75 make the intermediate elastic stitch. This vertically-oscillating movement of plate E and its adjuncts is accomplished by means of the lever C, Figs. 1, 2, and 3, which is clamped at one end by split sleeve C' to shaft 80 B' of oscillating device E⁴, while the other end, carrying adjustable roller c, is raised and lowered by the surfaces d' and d² of cam D. Reacting spring D² is provided at roller end of lever C. The cam D, as has been re- 85 marked, turns at one-half the speed of cam H⁴, which operates the dog-actuating ratchet-wheel on shaft G' which moves the ring F by means of pinion G². The cam D is mounted on shaft D', which revolves in suitable bearings d³ and is actuated by gear-wheel D³, which is driven by pinion D⁴ on shaft I by 90 means of pulley D⁵ from any source of power. (Not shown.) Shaft I has on its outer end the eccentric K³ and dual cam N, the functions and operations of which will be herein- 95 after described.

K, Figs. 1 to 10, inclusive, is the needle for carrying the thread T, Figs. 7, 8, and 9, or 100 yarn employed for joining the loops z and z' of the two pieces of knit fabric and may be operated by mechanism commonly employed in this class of machines and consisting of the oscillating arm k', having on its lower end clamping-surfaces k⁴ for holding the needle, 105 clamping-screw k⁵, and thread-guide k⁶, as shown in Figs. 4 and 6. The arm K' oscillates on stud k', which is adjustable in slot a in standard A', Fig. 4. This arm K' has near the needle-carrying end of the same a short 110 arm K⁰, on which is pivot k². This pivot is inserted in a follower K², which rests in annular way k³, (indicated in eccentric K³, Fig. 4,) and a complete revolution of said eccentric carries the needle to its forward limit of 115 throw and back.

With the needle K, I employ the looper L, Figs. 1 to 9, inclusive, and an actuating mechanism for so operating the looper as to produce in the thread T and between the 120 united loops of two pieces of knit fabric an elastic chain-stitch. My preferred construction of this looper L and the mechanism for operating the same is shown in Figs. 1, 2, 3, 4, 5, and 6. The looper is preferably made 125

of steel wire of diameter about one-eighth of one inch. It is provided with shank l to be inserted in the downward curved portion l^2 of the forward end of arm M' of lever M and secured by set bolt or screw l^3 , Fig. 4. This looper is properly curved downward and forward and is provided with looping-finger l^4 , as indicated by dotted lines in Fig. 4, and particularly shown in Figs. 6, 7, and 8. This looping-finger is caused to make a complete circuit of the point of the needle K , as illustrated in Fig. 10, after the same has been thrust forward to its limit and takes the thread T from the needle and retains it while the needle recedes and delivers the recently made loop of thread T to the needle again on its return.

The mechanism I at present prefer to employ in this invention to cause the needle and looper to perform the function above described consists of the oscillating arm K' , Fig. 4, carrying needle K , as before described, and bifurcated lever M , carrying the looper L , which is operated by the dual cam N . Said cam N carries on its smooth face the eccentric K^3 , and both revolve with shaft I . The proper relative arrangement of this cam and eccentric is shown in Figs. 4 and 5, and their adjustment for proper mutual operation is accomplished by means of the slot k^7 and set-screw k^8 . (Shown in said Figs. 4 and 5.)

The lever M has arms M' and M^2 and is provided with sleeve M^3 , Figs. 4, 5, and 6, which fits but moves freely on horizontal stud M^4 , secured on post M^5 by nut m^{3x} , as shown in Figs. 5 and 6. A reacting spiral spring m around sleeve M^3 exerts pressure against the lever M and holds arm M^2 in contact with face-cam n' on body N . (Shown in Fig. 5.) Arm M' , carrying the looper L , is provided with pin m^2 , Figs. 2, 3, 4, and 5, having engagement with tension-spring m^3 , the opposite end of which is secured to rigid bracket A' , and this spring serves to hold short horizontal projection m^4 on arm M^2 , Fig. 5, in constant contact with the peripheral cam n of cam-body N . Both of these cam-faces n and n' serve to operate the looper L constantly in proper relation to the needle for producing the elastic stitch, the peripheral cam n producing the vertical movements of the looping-finger to take the thread off and above the needle and dropping it again below the same, while the face-cam n' serves to produce the horizontal movements of the looper forward and back to complete the circuit of looping-finger around the needle.

More particularly, Figs. 4 and 5 show the cam N and eccentric K^3 and in position where the needle, with its thread, has passed through the loops of the fabrics to be joined to its greatest length of throw. The highest point 8 of face-cam n' holds lever M back, so that the looping-finger l^4 is just under the thread and back of the needle-eye k , as shown in

Figs. 5 and 7. The peripheral cam-surface 4 is now presented, as well as the face-cam surface 9 . The former moves the finger l^4 so that the looper L is raised above the needle, and the latter causes the same to travel forward, carrying the thread with it, as indicated by dotted lines in Fig. 7. The idle portion 1 of the peripheral cam n , being of less diameter than that of portion 3 , drops the looper below the first line of travel, and the idle surface 5 of the face-cam n' brings the looper to position shown in Fig. 8 still holding the thread. Meanwhile and during the time of the backward throw of the needle the eccentric H^4 , actuating-dog H' , has made one revolution and advanced one of the points f , so that a space is presented in the needle's path, as shown in Fig. 8, and a revolution of cam D , Fig. 3, has brought its short throw-surface d' into position, when reacting-spring D^2 , Fig. 3, will oscillate plate E and depress the points carrying the loops of the fabrics to be stitched so that they will be under the needle and looper and free from engagement with either, as shown by broken and dotted lines z in Fig. 2. The needle actuated by eccentric K^3 , Fig. 3, again advances, and arm M^2 , being pressed into portion 6 of the face-cam n' , quickly crowds the looper and its loop of thread r' forward to position shown in Fig. 9, and the portion 2 of the peripheral cam n tilts the looping-finger l^4 , so as to give a slight slackness to the thread. Then the needle passes through the loop on the heel of the looping-finger and takes it off, which operation is assisted by the enlarged opening between the heel and the thread produced by the chamfer l^5 , Figs. 7 and 8. Arm M^2 is now quickly moved back by the riding up on surface 7 of the face-cam n' and withdraws the looping-finger from the loop now formed, leaving the loop on the needle to be carried back to the line of stitching connecting the loops $z z'$ of the two pieces of fabric. The arm M^2 continues to be pressed back until it reaches highest surface-cam point 8 , where it will be ready to take the thread or yarn from the succeeding needle thrust and perform its function again with the next pair of loops to be joined. Thus the needle and looper form a stitch first through the loops of the two pieces of fabric, then one in the space between, then with the next pair of loops, then in the space, and so on, forming the stitches with the intermediate ones in the manner indicated by diagram Fig. 11, stitches z' and z being those connecting the loops of the fabric, and z^2 the intermediate ones. It is to be understood that while the peripheral points f are intermittently advanced the mechanism described for vertically oscillating the plate and ring-carrying points f operates so as to cause the needle to take a stitch on the point f while the plate is in normal position and then take one be-

tween the points and over the plate when said plate is tipped downward by the cam D through arm C.

Having described my invention, what I claim, and desire to secure by Letters Patent, is—

1. In a looping-machine, the combination with a stationary bed-plate, an arm having a sleeve supported above the plate, a circular plate, an oscillating device having its lower end portion secured to the center of said circular plate, the upper portion of the oscillating device working in the sleeve and mechanism for operating said oscillating device and 15 plate alternately toward and from said stationary base-plate.

2. In a looping-machine, the combination with a stationary base-plate, an arm having a sleeve and connected with said base-plate, a circular plate suspended from the sleeve, a ring, mounted on the circular plate, points on the ring for holding loops of two pieces of knit fabric, means for oscillating the circular plate, and a needle coöperating with the 25 points for the purpose specified.

3. In a looping-machine, the combination with a stationary base-plate, an arm provided with a sleeve at its end, an oscillating device, a circular plate carried by the oscillating device, a revolute ring carrying spaced points for receiving the loops of two pieces of knit fabric to be joined, means for actuating the oscillating device, and mechanism for intermittently rotating the ring. 30

4. In a looping-machine, the combination with a stationary base-plate, an arm provided with a sleeve, an oscillating device suspended from the sleeve, including a rigid circular plate, a revolute ring with points 40 adapted to be rotated on the circumferential portion of the circular plate, a gear on the ring, mechanism secured to the lower side of the circular plate and coacting with the gear for intermittently actuating the ring, and 45 means for actuating the oscillating device.

5. In a looping-machine, the combination with a stationary base-plate, an arm supported above and extended rearward from the base-plate, a circular plate suspended 50 from the arm and adapted to be oscillated, a circumferential way, formed in the circular plate, means for oscillating the plate, a ring rotating in the way, a series of points projecting from the ring for engaging the loops of two pieces of knit fabric to be joined, a gear on the lower side of the ring, a ratchet-wheel, a pinion actuated by the ratchet-wheel and engaging the gear, and a dog for actuating the ratchet-wheel. 55

6. In a looping-machine, the combination with a circular plate which is suspended and fixed from revolving, a metal ring carrying a series of points and adapted to be rotated intermittently on the circumferential portion 65 of said circular plate, a gear formed on the

lower side of the ring, a pinion mounted on the circular plate and meshing with the gear, means for intermittently rotating the gear, and means for oscillating the circular plate.

7. In a looping-machine, the combination with a circular plate which is fixed against rotation, a metal ring provided with a series of points for suspending two pieces of knit fabric by their loops, mechanism for intermittently rotating said ring and the series of 75 points in relation to said circular plate, a needle, and means for oscillating the circular plate.

8. In a looping-machine, the combination with a suspended circular plate fixed from 80 turning, a metal ring carrying points for suspending two pieces of knit fabric and adapted to be rotated in relation to said circular plate, a shaft supported from bearings fixed to the lower side of said circular plate, a ratchet-wheel, means for intermittently rotating the ratchet-wheel, mechanism between said metal ring and the ratchet-wheel for rotating the ring, a needle, and means for oscillating the circular plate. 85

9. In a looping-machine, a mechanism for suspending two pieces of knit fabric by the loops of the same, and for intermittently rotating said fabric, the said mechanism consisting of the combination of a circular plate 95 which is fixed from rotating, a ratchet-wheel, a dog for actuating the ratchet-wheel, a pinion revolved with said ratchet-wheel, a circular series of cogs provided on the lower side of the intermittently - rotating mechanism 100 from which the two pieces of knit fabric are suspended, and a reciprocating arm for actuating said dog, a needle, and means for oscillating the intermittently-rotated mechanism. 105

10. In a looping-machine, the combination with a stationary base-plate, an arm projected rearward from said base-plate and provided with a sleeve, an oscillating fabric-holding device suspended from the sleeve, including a rigid circular plate, a rotating device carried by the circular plate and adapted to hold two pieces of knit fabric suspended from their loops to be joined, and an adjustably-mounted lever mechanism for actuating the oscillating device. 110

11. In a looping-machine, the combination with a stationary base-plate, an arm projecting from the base-plate, a circular plate adapted to be vertically oscillated below the arm toward and from the base-plate, an oscillating device fixed to the center of the circular plate and pivoted to the arm, a circular way formed on the periphery of the plate, a rotating ring having an intermittent movement in said way, a series of points carried by said ring from which two pieces of knit fabric may be suspended by their loops between the rotating ring and the base-plate, means for moving the ring, a lever on the pivot of the oscillating device, means for lifting one end of the. 125 130

lever, and a reacting-spring for returning said lever.

12. In a looping-machine, the combination with a stationary base-plate provided with a 5 projecting arm, a circular plate suspended from said arm by an oscillating device between said arm and circular plate, a lever connected to said oscillating device, means for raising one end of said lever, a reacting 10 spring for returning the lever, a metal ring adapted to be rotated in relation to the circular plate and carrying points to engage with the loops of two pieces of knit fabric, mechanism for intermittently rotating the ring, 15 which comprises a ratchet-wheel, a reciprocating dog for rotating said ratchet-wheel, and a means for holding the ratchet-wheel after it is operated by the dog.

13. In a looping-machine, the combination 20 with a stationary base-plate, an arm projected rearward from the same and provided with a sleeve, an oscillating device including a circular plate fixed from turning, and suspended from the sleeve, an arm connected to 25 said oscillating device, a cam for operating the oscillating device, a ring of points mounted on the plate, mechanism, including a ratchet-wheel and a reciprocating dog, for rotating said ring of points, an eccentric for imparting a reciprocating motion to said dog, 30 and gearing to revolve the eccentric twice to one revolution of the cam.

14. In a looping-machine, the combination with a stationary base-plate; a circular plate, 35 a ring carrying a circular series of points for suspension of two pieces of knit fabric, mechanism for revolving the ring in relation to the base-plate, means for oscillating the circular plate and the rotating series of points toward 40 and from said base-plate, a reciprocating needle, and mechanism for oscillating the needle-point forward from said base-plate toward said rotating ring and return.

15. In a looping-machine, the combination 45 with a stationary base-plate, a circular plate adapted to be oscillated toward and from said base-plate, a ring carrying points for holding two pieces of fabrics suspended between said ring and base-plate, mechanism 50 for revolving the ring in relation to the base-plate, a reciprocating arm, an eccentric for imparting reciprocating motion to the lower end of the arm, a needle secured to the lower end of the arm and having its body carried 55 on a curve the radius of which extends from the center of motion of said arm to the shank of said needle, mechanism for vibrating said arm, and means for oscillating the plate.

16. In a looping-machine, the combination 60 with a stationary base-plate, a ring carrying a series of points from which two pieces of knit fabric may be suspended by their loops, means for revolving the ring in relation to the base-plate, means for oscillating the ring toward 65 and from the base-plate, an arm, a

pivot for said arm, a needle secured in the lower end of the arm and carried upward from its shank on a curve the radius of which extends from the needle-shank to the pivot of the arm, a cam, a follower pivoted to the suspended arm, and coöperating with the cam, the said needle-arm being oscillated twice by the cam to one oscillation of the ring of points.

17. In a looping-machine, the combination 75 with a stationary base-plate, a ring carrying a series of points to hold two pieces of knit fabric, mechanism for intermittently rotating said ring, mechanism for oscillating said ring, an oscillating needle-holding bar, a camway, 80 a follower in said way, a pivot connecting said follower with said needle-holding bar, the camway actuating the needle-bar twice to each oscillation of the ring - carrying points, so that the needle may be moved first 85 over a point and back and then forward over the space between said point and the next succeeding point.

18. In a looping-machine, the combination 90 with a ring carrying points from which loops of two pieces of knit fabric are suspended, mechanism for oscillating said ring and points, mechanism for intermittently rotating said ring, an oscillating needle - bar, a curved needle secured to the bar, mechanism 95 for oscillating the bar twice—once over a point and once over the space between said point and its succeeding one—to each oscillation of the ring of points, and also to each intermittent movement of the ring.

19. In a looping-machine, the combination 100 with a stationary base-plate, an intermittently-moving ring of points for suspension of two pieces of knit fabric by their loops, means for oscillating the ring, a needle adapted to be oscillated from the base - plate, a curved looper provided at its forward end with a looping-finger and a chamfer opposite said looping-finger, mechanism for actuating said needle as described, and mechanism operating said looper as stated for producing 105 the elastic chain of stitches for joining the loops of two pieces of fabric.

20. In a looping-machine, the combination 115 with a stationary base-plate, a curved needle, a suspended arm carrying said needle, an eccentric for actuating said arm with an oscillating movement, a ring carrying a circular series of points for suspending two pieces of knit fabric, by their loops, mechanism for rotating said ring and points intermittently, mechanism for oscillating said ring and points toward and from said needle, a looper having a curved body provided at its terminal end with a looping-finger and having a 120 chamfer opposite said finger, a lever operating said looper for oscillating the same toward and from said needle, a dual cam-body having peripheral cam depressions and elevations, and face-cam depressions and eleva- 125 tions, and face-cam depressions and eleva- 130

tions, means for holding said lever against both the peripheral cam and face-cam and for moving said looper laterally.

21. In a looping-machine, the combination with a looper having a curved body provided with a looping-finger and a chamfer opposite the said looper-finger, a laterally-movable lever carrying said looper, a dual cam-body having a peripheral face provided with elevations and depressions for oscillating the said lever, and a side face with elevations and depressions for moving said lever laterally and return.

22. A looping-machine including points for holding loops of fabric, a needle, means for oscillating the points toward and from the needle, including a pivoted arm, a cam for tilting the arm in one direction, means for tilting the arm in the opposite direction, and means for operating the needle toward and from the points.

SETH T. HARSHAW.
